DESIGN FOR A SCORE SHEET

Richard Fitz Power, Hampstead, London,
England

Application October 29, 1934, Serial No. 53,803
In Great Britain July 3, 1934

Term of patent 14 years

To all whom it may concern:

Be it known that I, Richard Fitz Power, a subject of the King of Great Britain, residing at Hampstead, London, N. W. 3, England, have invented a new, original, and ornamental Design for Score Sheets, of which the following is a specification, reference being had to the accompanying drawing, forming part thereof:

I claim:

The ornamental design for a score sheet as shown.

In testimony whereof I affix my signature.

RICHARD FITZ POWER.
